UNITED STATES PATENT OFFICE.

MARTIN LEWIS ALTOP, OF SACRAMENTO, CALIFORNIA.

DESIGN FOR A FINGER-BOARD GUIDE.

SPECIFICATION forming part of Design No. 29,045, dated July 12, 1898.

Application filed February 18, 1898. Serial No. 670,866. Term of patent 7 years.

To all whom it may concern:

Be it known that I, MARTIN LEWIS ALTOP, a citizen of the United States, residing at Sacramento, in the county of Sacramento and State of California, have invented and produced a new and original Design for Finger-Board Guides for Fretted Stringed Instruments; and I do hereby declare the following to be a full, clear, and exact description of the same.

Figure 1 in the drawings is a plan view of a finger-board guide, showing my design. Fig. 2 is a longitudinal view of the guide shown in Fig. 1.

My design is adapted for a guide attachment for finger-boards of stringed instruments, such as guitars and the like.

As shown by the drawings, the leading or essential feature of my design consists in a thin elongated piece of material A of the same general shape as the face side of the finger-board of the common type of stringed instrument—that is to say, the strip is of generally elongated tapered form having its sides cut away at C, the large end a distance substan-

tially equal to that part of the finger-board which lies on the body of the instrument. The strip A is provided with elongated transverse slots B, spaced apart distances corresponding with the distances between the frets 30 on the finger-board of the instrument for which the guide is adapted. Between the slots are longitudinal lines D, positioned correspondingly to the strings on the instrument for which the guide is adapted.

Between the slots B blank spaces E are left for any suitable indicating characters which it may be desirable to place on the guide.

Having thus described my invention, what I claim as new, and desire to secure by Letters 40 Patent, is—

The design for a guide for finger-boards, substantially as shown and described.

In witness whereof I have hereunto set my hand.

MARTIN LEWIS ALTOP.
